UNITED STATES PATENT OFFICE.

ALBERT E. VOGT, OF ROCHESTER, NEW YORK, ASSIGNOR TO VOGT MFG. & COACH LACE CO., OF ROCHESTER, NEW YORK, A CORPORATION OF NEW YORK.

FINISHING-STRIP.

1,243,903.

Specification of Letters Patent. Patented Oct. 23, 1917.

Application filed July 3, 1916. Serial No. 107,448.

To all whom it may concern:

Be it known that I, ALBERT E. VOGT, of Rochester, in the county of Monroe and State of New York, have invented certain 5 new and useful Improvements in Finishing-Strips; and I do hereby declare the following to be a full, clear, and exact description of the same, reference being had to the accompanying drawings, forming a part of 10 this specification, and to the reference characters marked thereon.

My invention relates to a finishing strip and has for its object to provide a strip adapted to be used as a border or edging for 15 various kinds of finish and particularly for the edging and binding of the inside finish of automobile bodies and other upholstered members. A further object of the invention is the provision of a flexible fabricated edg- 20 ing or finish strip adaptable for trimming the edges of various kinds of upholstered bodies. A still further object of the invention is to provide a flexible trimming and binding strip arranged to conceal the fas- 25 tening members by which said strip is secured. To these and other ends the invention consists in certain improvements and combinations of parts, all as will be hereinafter more fully described, the novel fea- 30 tures being pointed out in the claims at the end of the specification.

In the drawings:

Figure 1 is a view in perspective showing the finishing strip in unfolded position;

35 Fig. 2 is an enlarged detail sectional view through the strip as applied to a section of finish, the inner edge of the strip being shown in open position, and

40 Fig. 3 is a similar view with the inner edge folded over in position upon the body of the strip.

Similar reference characters throughout the several views indicate the same parts.

The finish or trimming strip embodied in 45 the several views of the drawing is adapted to serve as a binder for the edges of different kinds of finish as well as to present a neat and attractive border which may be readily applied to the finish. The inner and 50 intermediate or exposed portions 10 and 11 of the strip are preferably woven thicker than the outer portion 12 and intermediate or body portion 13, these latter portions being made relatively thin for the reason that 55 it is desired not to render the edging or

binding too bulky. The finish to which the strip is applied; designated at 14 in Figs. 2 and 3, may be of any desired material such as cloth or leather or any other material suitable for the purpose. Inclosed in the 60 outer exposed portion 11 of the strip is a filler 15 preferably in the form of a cord adapted for providing a beaded edge upon the outer side of the strip.

The extreme edge 12 of the strip is ex- 65 tended upon the intermediate or body portion 13, the two portions being connected at 16 preferably by stitching as indicated in Figs. 2 and 3. The securing brads or 70 nails 17 are driven through the relatively thin portions 12 and 13 of the strip and into the finish 14 and supports therefor (not shown) whereby both strip and finish are securely fastened in proper position. A 75 suitable quantity of adhesive material, des- 80 ignated at 18 is then applied to the parts 12 and 13 or to the back of the inner edge 10, after which said edge is folded into the position shown in Fig. 3 where it is held by the adhesive material.

While I have shown the finishing strip formed of fabricated material it will be understood that leather or other flexible and non-fabricated material may be used for the same purpose if desired, and that any 85 suitable fastening means may be substituted for the nails 17.

I claim as my invention:

1. A finishing strip formed of flexible material one edge of which is folded upon 90 the body of the strip and the other edge upon said first mentioned edge, and means positioned between the edges for holding them together.

2. A finishing strip one edge of which is 95 folded upon the body portion thereof and the other upon said first mentioned edge, means connecting said first mentioned edge and body, and means connecting the two edges.

3. A finishing strip having its outer edge folded upon the body portion thereof and its inner edge upon said outer edge, a filler inclosed by the first mentioned folded portion and means connecting said edges.

4. A finishing strip having its outer edge folded upon the body portion thereof and its inner edge upon said outer edge, a filler inclosed by the first mentioned folded portion, means connecting said first mentioned

folded portion and body and means connecting said edges.

5. A finishing strip having one of its edges folded upon the body portion thereof and its other edge upon the first mentioned edge and a filler inclosed by one of the folded edges.

6. A finishing strip having relatively thick and thin edge portions and relatively thick and thin intermediate portions, said thin edge portion being folded upon the intermediate thin portion and said thick edge portion upon the folded thin edge portion.

7. A finishing strip having relatively thick and thin edge portions and relatively thick and thin intermediate portions, said thin edge portion being folded upon the intermediate thin portion and said thick edge portion upon both of said thin portions.

8. The combination with a body finish, of a flexible finishing strip having one of

its edges folded upon itself and its other edge upon the first mentioned edge, and means securing said strip upon the finish, 25 said means being concealed by the second mentioned folded portion.

9. The combination with a body finish, of a flexible finishing strip having one of its edges folded upon itself and its other edge 30 upon the first mentioned edge, means securing said strip upon the body finish and means between said folded edges connecting the same.

10. A finishing strip having spaced portions of substantially the same thickness connected by a relatively thick portion, the spaced portions being folded one upon the other and means connecting the same. 35

ALBERT E. VOGT.
